TANKS

Alfred W. Freeman, Jackson Heights, N. Y.

Application March 11, 1949, Serial No. 1,350

Term of patent 3½ years

(Cl. D61—1)

To all whom it may concern:

Be it known that I, Alfred W. Freeman, a citizen of the United States, residing at Jackson Heights, New York, in the county of Queens and State of New York, have invented a new, original, and ornamental Design for a Film Pack Adaptor for Developing Tanks, of which the following is a specification, reference being had to the accompanying drawing, forming a part thereof.

In the drawing:

Fig. 1 is a perspective view of a film pack adaptor for developing tanks showing my new design;

Fig. 2 is a bottom perspective view of the same; and

Fig. 3 is a perspective view of the film sepa-

rator, shown removed from the tank.

I claim:

The ornamental design for a film pack adaptor for developing tanks, as shown.

ALFRED W. FREEMAN.
